SAMUEL C. McKEOWN, OF NEWARK, NEW JERSEY, ASSIGNOR TO SPLITDOOR ELECTRICAL COMPANY, OF NEWARK, NEW JERSEY.

IGNITION BREAKER BOX.

Application filed August 30, 1920. Serial No. 407,041.

To all whom it may concern:

Be it known that I, SAMUEL C. McKEOWN, a citizen of the United States, residing at Newark, in the county of Essex and State of New Jersey, have invented certain new and useful Improvements in Ignition Breaker Boxes, of which the following is a description, reference being had to the accompanying drawing, and to the figures of reference marked thereon.

In the construction of ignition breaker boxes, there is ordinarily provided a so-called stationary contact member and an oscillating member operated by a cam contacting periodically therewith. In order to time the spark in an internal combustion engine, it has been customary to mount both contact members on a base shiftable about the axis of the cam. This necessarily entailed a flexible electric connection to the so-called stationary contact member. In the course of time this flexible lead due to the constant shifting or flexing would break, thus interrupting the ignition circuit.

One object of my invention is to so mount the contact making members on the breaker box, that no flexible lead is necessary for connection with the stationary contact member, while enabling the proper timing operation to be performed.

Sometimes it has been found difficult to start an engine because of the accumulation of a film of oxide, oil or other non-conductive material on the contact makers.

It is another object of my invention to so mount the contact members that this film of non-conductive material may be removed by movement of the timing means.

Another object of my invention is to mount the oscillating contact member in a wide bearing so that the side blow and push of the operating cam will not cause the member to wobble.

A further object of my invention is to mount the contact points so that a more even wear results on the points than in the ordinary construction of contact breakers.

A still further object of this invention is to provide readily adjustable means for initial timing of the breaker box.

Other and further objects of my invention will be apparent to those skilled in the art after consideration of the specification and the drawings attached hereto, in which—

Figure 1 is an end view of my complete

breaker box with the cover removed, the cover retaining spring being swung aside, and a portion being broken away.

Figure 2 is a section on the line 2 of Figure 1 looking in the direction of the arrow 60 and with the cover in place.

Figure 3 is a side view of my complete breaker box, and

Figure 4 is a perspective view of my oscillatory contact member.

Figure 5 is a section on the line 5 of Figure 1 looking in the direction of the arrow 65, certain parts being removed.

Referring now particularly to the drawings in which like numbers refer to the same parts in the various figures, 5 is a cup shaped box provided with three apertures 6. Through two of these apertures suitable machine screws are passed for fastening the cup shaped box to a support as to a magneto frame. In the other aperture a post 7 is seated provided at its lower end with a machine screw thread 8 passing through the aperture and adapted to be screwed into the support. At the upper end of the post is 75 secured a spring tongue 9 adapted to hold a cover 10 in place.

The base of the cup shaped box is recessed at 11 so as to permit the passage into the cup shaped member of a shaft provided with an operating cam as is shown in the patent to Mason 1,226,982 granted May 22, 1917. Integral with this cup shaped box is a projecting support 12 in a recessed portion 13 of which is seated a wick 14, the wick being impregnated with a lubricant and adapted to keep a thin film of said lubricant on the cam surface. To the end of the support and suitably insulated therefrom, as by insulation 15, is fastened a contact supporting member 16 by means of two screws 17, 17 and on this member is mounted the contact carrying element 18 by means of a screw 19 and two centering pins 20. In this contact carrying element and centrally of the box is adjustably mounted the stationary contact 21. The contact supporting element is also provided with a screw 22 for the proper attachment of the terminal of a low tension wire 23. Also secured in the base 5 is a pin 24 for a purpose to be hereinafter described.

Fitting snugly within the cup shaped member is an oscillating contact supporting ring 25 provided with two ears 26 in 100 105 110

which is mounted a pivot pin 27 supporting the oscillatable contact member 28. The oscillatable contact member is hung from said pin by means of two arms 29 and is provided with a contact point 30 also centrally located in the box and cooperating with the contact point 21. A flexible connection, preferably of woven copper is attached to a screw 31 on the contact member and is 10 grounded to the ring by any suitable means.

Into the upper portion of the ring is threaded a brass screw 32 chambered so as to seat a spring 33 which presses against the oscillatable contact member 28 so as to normally force the two contacts 21 and 30 into engagement with one another. On the lower side of the member is mounted a bumper 34 of fibre or other suitable material adapted to contact with the operating cam so as to 15 cause the contacts 21 and 30 to make and break contact. This bumper is encompassed on three sides by downwardly turned lugs 35 and on the fourth side by the body portion proper of the oscillatable contact member 28. Suitable pins 36 are provided for securely 20 retaining the bumper in place. These means securely hold the fibre bumper in place.

It is evident that by rotating the ring 25 by any suitable means, that the angular position of the bumper with respect to the cam shaft may be altered thereby delaying or advancing the moment of contact of the contact members with respect to the angular position of the shaft. The means for rotating 25 the ring 25 comprises an annular toothed ring 37 integrally cast with or suitably secured to the ring 25. Cooperating with this ring is a second toothed annular ring 38 centered on a hub 39 of the ring 25 and provided with an operating arm 40 oscillated 30 by the driver of the automotive vehicle as will be readily understood. In order to retain the two annular members in place, a retaining ring 41 of slightly less external diameter than the ring 38 is superimposed on the annular ring 38 and is fastened to the ring 25 by means of co-operating lugs 42 and 43 and the screws 44. To limit the angular movement of the ring 25 a recess 45 is cut in the ring 25, the end walls of 35 which co-operate with the pin 24 in the cup shaped member 5. A co-operating hole 46 in the box 5 and recess 47 in the ring 25 enable the passage of the low tension wire 23 40 there through for securing to the member 16 by screw 22. The cover 10 fits snugly around the retaining ring 41 and abuts the annular ring 38.

To remove the ring 25 for inspection or 45 repair of contact 30, it is merely necessary to loosen the screw 19 and to lift the contact carrying member 18 slightly to clear the pins 20, then by swinging the member 18 about its pivot 19 into line with the supporting member 16, all obstruction to the removal of

the ring 25 is removed and the same may be pulled out of the box.

By slightly loosening the screws 44, the teeth on the two annular rings being very shallow, the ring 38 may be slipped around the hub 39 to initially position the relative position of arm 40 and bumper 34 for proper timing.

When it is found that the engine is hard to start because of ignition trouble, by 75 jiggling the arm 40 the two contact surfaces 21 and 30 are made to rotate one upon the other, thereby obtaining clean contact surfaces and enabling a better spark to be produced within the cylinders of the engine.

It will also be noted that the two contacts are at a different angle to each other in retarded and advanced position of the timing means, which results in a more even wear 80 of the contact points than if the contacts were not rotated relative to one another. It should further be noted that this takes place without altering the working gap between the points, thus permitting the use of this construction on vibrators in general.

It is apparent that with the wide bearings afforded by the pin 27 and the arms 29, there is little wobbling of the oscillatory contact member possible and more accurate timing 85 with little wear results.

Having thus described my invention, which is capable of embodiment in many different forms, what I claim is:

1. In a breaker box a pair of co-operating contacts, one of said contacts being fixed in position, the other of said contacts having only two motions, one a motion of oscillation and the other one of rotation, the center of rotation being in said stationary contact and means to operate said other contact independently of the rotational movement thereof.

2. In a breaker box a box member, a stationary contact mounted thereon, a ring member rotatable within the box member, an oscillatable contact mounted on said ring member, both said contacts co-operating substantially at the center of rotation of said ring member.

3. In a breaker box, a pair of co-operating contacts, one of said contacts being fixed in position, the other of said contacts being movable and having two motions, one a motion of oscillation and the other one of rotation with means for rotating the same, the center of rotation being in said stationary contact, and means independent of said rotating means connected with said movable contact operated upon periodically to 120 oscillate said movable contact.

4. In a breaker box a box member, a stationary contact mounted thereon, a ring member rotatable within the box member, an oscillatable contact mounted on said ring mem-

ber, both said contacts co-operating substantially at the center of rotation of said ring member, and means connected with said movable contact operated upon periodically to oscillate said movable member.

5. In a breaker box a box member, a stationary contact mounted thereon, a ring member rotatable within the box member, means for rotating the ring member, an oscillatable contact mounted on said ring member, both said contacts co-operating substantially at the center of rotation of said ring member.

10. In a breaker box a box member, a stationary contact mounted thereon, a ring member rotatable within the box member, means for rotating the ring member, an oscillatable contact mounted on said ring member, both said contacts co-operating substantially at the center of rotation of said ring member, and means connected with said movable contact operated upon periodically to oscillate said movable member.

15. 6. In a breaker box a box member, a stationary contact mounted thereon, a ring member rotatable within the box member, means for rotating the ring member, an oscillatable contact mounted on said ring member, both said contacts co-operating substantially at the center of rotation of said ring member, and means connected with said movable contact operated upon periodically to oscillate said movable member.

20. 7. A breaker box, comprising a cup shaped box member, a ring member rotatably mounted therein, a reciprocable contact member extending into the center of rotation of and carried by the ring member and

25. a stationary contact member mounted on the box member provided with means whereby the same may be readily swung aside to permit removal of said ring member.

30. 8. A breaker box comprising a box member a ring member rotatably mounted therein, a reciprocable contact member extending into the center of rotation of and carried by said ring member, a stationary contact member mounted on the box mem-

ber, a toothed annulus co-operating with 40 said first annulus, and a clamping ring overlying said second annulus and secured to said ring member.

9. In a breaker box, an oscillatable contact member comprising a contact bearing 45 portion, a bumper carrying portion and an intermediate portion provided with two arms, said arms being widely spaced apart and provided with means whereby the contact member may be pivotally mounted. 50

10. In a breaker box, a box member, a stationary contact mounted thereon, a ring member rotatable within the box member, a reciprocable contact mounted on said ring member, both said contacts co-operating 55 substantially at the center of rotation of said ring member.

11. In a breaker box, a box member, a stationary contact mounted thereon, a ring member rotatably mounted within the box 60 member, a reciprocable contact mounted on said ring member, both said contacts co-operating substantially at the center of rotation of said ring member, and means connected with said movable contact operated upon periodically to reciprocate said movable member.

12. In a breaker box, a box member, a stationary contact mounted thereon, a ring member rotatable within the box member, 70 means for rotating the ring member, a reciprocable contact mounted on said ring member, both said contacts co-operating substantially at the center of rotation of said ring member. 75

In testimony whereof, I affix my signature.

SAMUEL C. McKEOWN.
